PHOTOTUBE CONTROL OF GRID-GLOW
TUBES

Lawrence R. Quarles, Wilkinsburg, Pa., assignor to Westinghouse Electric & Manufacturing Company, East Pittsburgh, Pa., a corporation of Pennsylvania

Application June 10, 1932, Serial No. 616,481

11 Claims. (Cl. 250—41.5)

My invention relates to translating apparatus and has particular relation to translating apparatus of the type incorporating gas filled electric discharge devices.

- 5 An electric discharge device of the type utilized in the practice of my invention ordinarily comprises a cathode of the unexcitable or the excitable type, an anode and a control electrode all immersed in a gaseous medium. The device 10 has substantially two conditions: a deenergized condition and an energized condition, and it is capable of only abrupt transition from one condition to the other. Potentials are impressed between the principal electrodes of the device and 15 between its control electrode and its principal electrodes and the electrical condition of the device is dependent on the relative values of the potentials. To facilitate explanation in the present case the potential impressed between the 20 principal electrodes shall be designated as the principal potential and the potential impressed between the control electrode and a principal electrode shall be designated as the control potential.
- 25 To each value of principal potential corresponds a value of control potential which may be termed the limiting control potential. As long as the control potential applied to a device remains below the limiting control potential for the 30 principal potentials applied the device remains deenergized. However, as soon as a control potential greater than the limiting control potential is applied to the device it at once becomes energized and remains energized, regardless of 35 changes in the control potential until the principal potential is reduced to zero or a negative value with reference to the cathode of the device.

It is an object of my invention to provide a 40 translating system of the type incorporating an electric discharge device in which the electric discharge device shall be normally deenergized and shall be energized to deliver its maximum output by a shift in phase of the control potential applied thereto, relative to the principal potential applied.

A further object of my invention is to provide 45 a translating system of the type incorporating an electric discharge device in which the device shall be normally deenergized, and shall be capable of being so energized by a shift in the phase of the control potential applied thereto relative to the principal potential applied thereto that the device shall deliver its maximum output when 50 it is so energized.

An incidental object of my invention is to provide a translating system incorporating a gas-filled electric discharge device, and a photo-sensitive trigger in which the electric discharge device shall be normally deenergized when the photo-sensitive trigger is unexcited, and shall be energized by the application of exciting radiations to the photo-sensitive trigger in such manner that it shall deliver its maximum output for a predetermined excitation of the photo-sensitive trigger; the output and the corresponding excitation being always the same for any predetermined system of circuit constants.

More concisely stated, it is an object of my invention to provide a translating system of the type incorporating an electric discharge device in which the constants shall be so disposed and so arranged relative to the trigger element that by a predetermined small variation of the trigger element a comparatively large variation in 20 the current output of the electric discharge device shall be attained.

According to my invention, I provide a translating system incorporating an electric discharge device which is so connected in a circuit with 25 an alternating-current power supply source that the potential impressed between the principal electrodes is in opposite phase to the potential impressed between the control electrode and one of the principal electrodes. The potentials are 30 of such magnitude that the device is thereby maintained in deenergized condition.

When it becomes desirable to energize the electric discharge device a trigger element in the control circuit is so varied that the phase of the 35 control potential is shifted relative to the principal potential in such a sense that the electric discharge device is energized to deliver substantially its maximum current output.

The novel features that I consider characteristic of my invention are set forth with particularity in the appended claims. The invention itself, however, both as to its organization and its method of operation, together with additional objects and advantages thereof, will best be understood from the following description of specific embodiments when read in connection with the accompanying drawing, in which:

Figure 1 is a graph illustrating the characteristics of an electric discharge device of the type utilized in the practice of my invention;

Fig. 2 is a diagrammatic view showing an embodiment of my invention;

Fig. 3 is a vector diagram illustrating the relation between the potentials applied to the 55

terminals of a system such as is shown in Fig. 2; Fig. 4 is a diagrammatic view showing a modification of my invention;

Fig. 5 is a diagrammatic view showing another modification of my invention;

Fig. 6 is a vector diagram illustrating the relation between the potentials impressed across the elements of a system such as is shown in Fig. 5;

10 Fig. 7 is a diagrammatic view showing a further modification of my invention;

Fig. 8 is a vector diagram corresponding to Fig. 7.

15 Fig. 9 is a diagrammatic view showing still another modification of my invention; and

Fig. 10 is a vector diagram corresponding to Fig. 9.

20 In Fig. 1, the potential impressed between the principal electrodes of an electric discharge device, of the type utilized in the practice of my invention, is represented by a sine curve 1, and the control potential is represented by a second sine curve 3, substantially in opposite phase to the first sine curve. As is apparent 25 from the graph the time variable is plotted as abscissa and the magnitude variable is plotted as ordinate.

30 The limiting control potential is represented as a substantially flat curve 5. The principal potential curve 1 to which the limiting control potential curve 5 is related is, as is shown, the central half-cycle 7 of the curve 1 representing the potentials impressed between the principal electrodes. To every point on the half-cycle 7 35 of the principal potential curve 1 a point on the limiting potential curve 5 corresponds, and if control potentials are applied which fall above the limiting control potential curve 5, at points corresponding to the principal potential applied, 40 the electric discharge device becomes energized. If the control potentials fall below this curve, the electric discharge device remains deenergized if it has not already been energized. It is to be noted that as shown in Fig. 1, the negative half- 45 cycle 9 of the control potential corresponding to the positive half-cycle 7 of the principal potential falls entirely below the limiting potential curve. If the constants of a system are such that the potential relations as shown in this figure 50 prevail, the electric discharge device in the system is in deenergized condition.

55 As can be seen from the view, the control potential curve 5 is symmetric about the axis 11 of the two half-cycle curves 7 and 9 corresponding thereto, which represent the positive principal potential half-cycle and the negative control potential half-cycle. It is to be noted that if only the magnitude and not the phase of the control potential curve 3 is changed, the control potential 60 curve when it is sufficiently raised may intersect the limiting control potential curve 5 at two points equidistant from the line of symmetry 11, and the output of the system corresponding to one point or the other, will then depend on random conditions of the system. On the other hand, if the phase of the control potential curve 3 is shifted in such manner that the curve moves towards the right a small shift in phase will cause the control potential curve 3 to intersect the limiting 65 control potential curve 5 substantially near the right-hand terminal of the positive half-cycle 7 of the principal potential curve 1, and in consequence thereof, the power output of the electric discharge device, which is a function of the fraction of the positive period during which the elec-

tric discharge device remains energized, will be substantially a maximum.

5 As has been explained hereinabove, the principal object of my invention is to provide a system in which the condition of the electric discharge device is varied by phase shift variation of the control potential, rather than by magnitude variation of this potential, and in which the direction of the shift is such that the output of the electric discharge device is a maximum.

10 As shown in Fig. 2, the system whereby my invention is practiced comprises an electric discharge device 13, including preferably an excitable cathode 15, an anode 17 and a control electrode 19, all immersed in a gaseous medium. Power is supplied to the electric discharge device through a power supply transformer 21, the secondary 23 of which is equipped with two terminal taps 25 and 27 and an intermediate tap 29.

15 The cathode 15 of the electric discharge device 20 13 is connected to the intermediate tap 29 while the anode 17 is connected to one terminal tap 25 through the exciting coil 31 of a relay 33 which symbolizes any load that it may be found desirable to feed through the electric discharge device. 25

20 The control electrode 19 of the electric discharge device 13 is connected to the other terminal tap 27 of the secondary 23 through a comparatively high impedance 35, preferably, but not necessarily, a resistor. The terminal taps of the 30 transformer are coupled to a series network comprising a capacitor 37 of comparatively high magnitude and a resistor 39. A photo-sensitive device 41 is connected between the control electrode 19 and the junction-point 43 of the capacitor 37 35 and resistor 39; the cathode 45 of the device being connected to the control-electrode 19 and the anode 47 being connected to the junction point 43.

40 The vector diagram corresponding to the circuit of the type shown in Fig. 2 is illustrated in Fig. 3. The potentials applied between the taps 27, 29 and 25 of the secondary 23 are represented by two horizontal vectors 49 and 51. The potential impressed across the resistor 39 that is in series with the capacitor 37 is represented by a vector 53 at a predetermined angle to the horizontal vectors, while the potential impressed across the capacitor 37 is represented by a vector 55 at right angles to the vector 53 representing the resistor potential. It will be noted that this representation is in accordance with the physical fact that the individual potentials impressed across the resistor 39 and capacitor 37 are in space quadrature phase relationship with each other. 50

45 The potential impressed across the resistor 39 55 that is connected in series with the capacitor 37 is equal to the sum of the potentials that are impressed across the resistor 35 connected to the control electrode 19 and the cathode 45 of the photo-sensitive device 41. The photo-sensitive device is of a type that has the property of a capacitor when it is de-energized, and consequently, the potentials impressed across the resistor 35 associated with the photo-sensitive device and across the photo-sensitive device in its de-energized condition, may be represented by two vectors 57 and 59 at right angles to each other, which, together with the vector 53 representing the potential impressed across the resistor 39 in series with the capacitor 37, form a right 60 triangle. 65

70 It is to be noted that the vector 61 representing the potential impressed between the control electrode 19 and the cathode 15 of the electric discharge device 13 is substantially 180° out of phase 75

with the vector 51 representing the potential impressed between the principal electrodes 15 and 17 of the electric discharge device 13. The potentials applied to the system are thus substantially represented by the principal potential and the control potential curves 1 and 3 of Fig. 1. For this relative condition of the potentials the electric discharge device 13 is in de-energized condition and remains so unless the condition of the photo-sensitive trigger 41 is disturbed.

However, when the photo-sensitive device 41 is energized from the suitable light-source 63, the vector 61 in Fig. 3 representing the potential impressed between the control electrode 19 and the cathode 15 is rotated in a clockwise direction and is represented in its new position by the broken vector 65. It will be noted that this rotation of the vector 61 corresponds to a shift of the control potential in a direction such that the phase difference between the control potential and the principal potential is smaller than it was before the photo-sensitive device 41 was energized. Essentially, therefore, the control potential assumes a condition represented by the broken-line curve 67 in Fig. 1.

It will be noted that the broken-line curve 67 intersects the limiting control potential curve 5 at a point very near to the left-hand terminal of the positive half-cycle 7 of the principal potential curve 1. That is to say, the control potential is now greater than the limiting potential at a point very near to the beginning of the positive half-cycle of the principal potential. The electric discharge device 13, therefore, becomes energized at this point and remains energized during the whole of the positive half-cycle, the maximum of current output being thus delivered by the electric discharge device to the load 33.

In the practice of my invention, the electric discharge device 13 is a mercury-vapor filled device having a cathode 15 of the oxide-coated type and being capable of delivering a maximum crest plate current of 6 amperes and a maximum average plate current of 4 amperes. The transformer 21 is of a type such that a potential of 220 volts is delivered between each terminal tap 25 and 27 and the intermediate tap 29. The photo-sensitive device 41 is of the caesium-oxide cathode high-vacuum type. The capacitor 37 has a magnitude of 1 microfarad and the resistor 39 associated therewith has a magnitude of the order of 10,000 ohms. The resistor 35 connected to the control electrode 19 of the electric discharge device 13 has a magnitude of the order of 100 megohms.

In apparatus of the type shown in Fig. 4, the capacitor 37 of the system shown in Fig. 1 is replaced by an inductor 69. It will be noted that by reason of the difference in electrical character between a capacitor and an inductor, the position of the resistor 39 associated with the inductor is now reversed, the resistor 39 being connected where the capacitor 37 of the system of the type shown in Fig. 2 is connected, and the inductor 69 being connected where the resistor 39 in the latter system is connected. The vector diagram of the system is the same as the vector diagram shown in Fig. 3, and the operation of the system is correspondingly similar to the operation of the system shown in Fig. 2.

The apparatus of the type shown in Fig. 5 is different from the apparatus of the type shown in Fig. 2 only by the fact that the resistor 35 associated with the photo-sensitive device 41 is replaced by a capacitor 71. The vector diagram as

shown in Fig. 6, is thus only modified to correspond to the fact that since the capacitor 71 and the photo-sensitive device 41 now both have the property of a capacitor, the potential impressed across the two elements, (that is to say, across the resistor 39) is in phase with the potentials impressed across the elements individually. The potential impressed between the control electrode 19 and the cathode 15 is now, as it is for a system of the type shown in Fig. 2, substantially in opposite phase to the potential impressed between the principal electrodes 15 and 17 as long as the photo-sensitive device 41 remains deenergized.

However, when the photo-sensitive device is energized, the potential impressed across the capacitor 71 associated with the photo-sensitive device 41 and the potential impressed across the photo-sensitive device 41 no longer remain in phase with each other and the situation is represented approximately by the broken-lines 73 and 75 as shown in Fig. 6.

However, as in the system of the type shown in Fig. 2, the phase of the control potential is shifted in such a sense that the control potential is brought more nearly in phase with the potential impressed across the principal electrodes.

The apparatus of the type shown in Fig. 7 corresponds to the apparatus of the type shown in Fig. 4 in that the capacitor 37 of the system shown in Fig. 5 is replaced by an inductor 69, and the impedances connected across the terminals 25 and 27 of the supply transformer secondary 23 are suitably repositioned to provide for the difference in the electrical character of an inductor and capacitor. As can be seen from Fig. 8, the vector diagram corresponding to Fig. 7 is similar to the vector diagram shown in Fig. 6 which corresponds to the system shown in Fig. 5.

The system shown in Fig. 9 is ordinarily designated as the reverse system. It is to be noted that this system differs from the system shown in Fig. 2 by the fact that the photo-sensitive trigger 41 and the resistor 35 are interchanged in position. Corresponding changes may also be made in the systems shown in Figs. 4, 5 and 7 to attain corresponding reverse circuits.

In systems of the type shown in Fig. 9 the electric-discharge device 13 is deenergized when the photo-sensitive trigger 41 is excited to a predetermined extent. When the excitation of the photo-sensitive device is sufficiently decreased, the electric discharge device 13 is energized and delivers substantially its maximum output in the same manner as does the device in the systems shown in Fig. 1.

In the vector diagram shown in Fig. 10 which corresponds to the circuit shown in Fig. 9 the vector 61 corresponding to the control potential is rotated in a clockwise direction when the illumination impinging on the photo-sensitive device 60 is decreased rather than when it is increased. The broken vector 65 shows its changed position for an increase in excitation of the photo-cell.

It is apparent of course, that the constants utilized in the actual practice of my invention with systems of the type shown in Figs. 4, 5, 7 and 9, may be derived from the constants utilized in systems of the type shown in Fig. 2. The values of the inductors and capacitors are such as to correspond to the impedance values of the impedances utilized in the apparatus shown in Fig. 2. Thus, the inductor 69, utilized in systems of the type shown in Figs. 4 and 7 is of such magnitude as to correspond to the capacitor 37 utilized in the system of Fig. 2. On the other hand, the

capacitor 71 utilized in the systems shown in Figs. 5 and 7 has a magnitude which is of the order of 25 micro-microfarads to correspond to the 100 megohm resistor utilized in apparatus of 5 the type shown in Fig. 2.

My invention has been shown herein as applied to a particular system and a gas-filled hot-cathode electric discharge device 13 of a particular type has been shown as utilized in the practice thereof. It is to be understood that my invention may be equally as well practiced with systems incorporating electric discharge devices of other types, such as mercury-pull devices, having make-alive and keep-alive electrodes, high- 10 vacuum electric discharge devices, and cold cathode gas-filled electric discharge devices.

Although I have shown and described certain specific embodiments of my invention, I am fully aware that many modifications thereof are possible. My invention, therefore, is not to be restricted except insofar as is necessitated by the prior art and by the spirit of the appended 15 claims.

I claim as my invention:

25 1. Translating apparatus comprising an electric discharge device including a control electrode and a plurality of principal electrodes immersed in a gaseous medium, means, including a transformer having a secondary equipped with an intermediate tap and a plurality of terminal 30 taps, for applying potentials between the electrodes of said electric discharge device, means for connecting the principal electrodes of said device between a terminal tap and said intermediate tap of said secondary to maintain a predetermined potential between said principal electrodes, an impedance, means for connecting said impedance between said control electrode and the other terminal tap of said secondary, a plurality 35 of additional impedances, means for connecting said additional impedances between the terminal taps of said secondary, a further impedance, means for connecting said further impedance between the control electrode of said 40 device and the junction point of the impedances that are connected between the terminal taps of said secondary, said impedances cooperating to normally maintain the potential between the control electrode and one principal electrode of 45 said electric discharge device substantially in opposite phase to the potential between the principal electrodes of said device thereby to maintain said device in deenergized condition and means for varying the condition of said last- 50 named impedance to shift the phase of the potential impressed between said control electrode and said principal electrode of said device relative to the potential impressed between said principal electrodes thereby to energize said device.

60 2. Translating apparatus comprising an electric discharge device including a control electrode and a plurality of principal electrodes immersed in a gaseous medium, means, including a transformer having a secondary equipped with an intermediate tap and a plurality of terminal 65 taps, for applying potentials between the electrodes of said electric discharge device, means for connecting the principal electrodes of said device between a terminal tap and said intermediate tap of said secondary to maintain a predetermined potential between said principal electrodes, an impedance means for connecting said impedance between said control electrode and the other terminal tap of said secondary, a plurality 70 of additional impedances, means for connecting said additional impedances between the terminal taps of said secondary, a photo-sensitive device, said device being normally deenergized, means for 75

pacitor and a resistor, means for connecting said capacitor and said resistor between the terminal taps of said secondary, a further impedance, means for connecting said further impedance between the control electrode of said device and the junction-point of the capacitor and resistor that are connected between the terminal taps of said secondary, said impedances cooperating to normally maintain the potential between the control electrode and one principal electrode of 10 said electric discharge device substantially in opposite phase to the potential between the principal electrodes of said device thereby to maintain said device in deenergized condition and means for varying the condition of said last- 15 named impedance to shift the phase of the potential impressed between said control electrode and said principal electrode of said device relative to the potential impressed between said principal electrodes thereby to energize said device. 20

3. Translating apparatus comprising an electric discharge device including a control electrode and a plurality of principal electrodes immersed in a gaseous medium, means, including a transformer having a secondary equipped with 25 an intermediate tap and a plurality of terminal taps, for applying potentials between the electrodes of said electric discharge device, means for connecting the principal electrodes of said device between a terminal tap and said intermediate tap of said secondary to maintain a predetermined potential between said principal electrodes, an impedance, means for connecting said impedance between said control electrode and the other terminal tap of said secondary, an inductor and a resistor, means for connecting said inductor and said resistor between the terminal taps of said secondary, a further impedance, means for connecting said further impedance between the control electrode of said device and the junction point of the inductor and resistor that are connected between the terminal taps of said secondary, said impedances cooperating to normally maintain the potential between the control electrode and one principal electrode of 30 said electric discharge device substantially in opposite phase to the potential between the principal electrodes of said device thereby to maintain said device in deenergized condition and means for varying the condition of said last- 35 named impedance to shift the phase of the potential impressed between said control electrode and said principal electrode of said device relative to the potential impressed between said principal electrodes thereby to energize said device. 40

45 4. Translating apparatus comprising an electric discharge device including a control electrode and a plurality of principal electrodes immersed in a gaseous medium, means, including a transformer having a secondary equipped with an intermediate tap and a plurality of terminal 50 taps, for applying potentials between the electrodes of said electric discharge device, means for connecting the principal electrodes of said device between a terminal tap and said intermediate tap of said secondary to maintain a predetermined potential between said principal electrodes, an impedance, means for connecting said impedance between said control electrode and the other terminal tap of said secondary, a plurality 55 of additional impedances, means for connecting said additional impedances between the terminal taps of said secondary, a photo-sensitive device, said device being normally deenergized, means for 60

65 5. Translating apparatus comprising an electric discharge device including a control electrode and a plurality of principal electrodes immersed in a gaseous medium, means, including a transformer having a secondary equipped with an intermediate tap and a plurality of terminal 70 taps, for applying potentials between the electrodes of said electric discharge device, means for connecting the principal electrodes of said device between a terminal tap and said intermediate tap of said secondary to maintain a predetermined potential between said principal electrodes, an impedance, means for connecting said impedance between said control electrode and the other terminal tap of said secondary, a plurality 75 of additional impedances, means for connecting said additional impedances between the terminal taps of said secondary, a photo-sensitive device, said device being normally deenergized, means for

- connecting said normally deenergized photo-sensitive device between the control electrode of said device and the junction point of the impedances that are connected between the terminal taps of said secondary, said photo-sensitive device and said impedances cooperating to normally maintain the potential between the control electrode and one principal electrode of said electric discharge device substantially opposite phase to the potential between the principal electrodes of said device thereby to maintain said device in deenergized condition and means for energizing said photo-sensitive device to shift the phase of the potential impressed between said control electrode and said principal electrode of said device relative to the potential impressed between said principal electrodes thereby to energize said device.
5. Translating apparatus comprising an electric discharge device including a control electrode and a plurality of principal electrodes immersed in a gaseous medium, means, including a transformer having a secondary equipped with an intermediate tap and a plurality of terminal taps, for applying potentials between the electrodes of said electric discharge device, means for connecting the principal electrodes of said device between a terminal tap and said intermediate tap of said secondary to maintain a predetermined potential between said principal electrodes, a photo-sensitive device, said device being normally energized, means for connecting said normally energized photo-sensitive device between said control electrode and the other terminal tap of said secondary, a plurality of impedances, means for connecting said impedances between the terminal taps of said secondary, an additional impedance, means for connecting said additional impedance between the control electrode of said device and the junction point of the impedances that are connected between the terminal taps of said secondary, said photo-sensitive device and said impedances cooperating to normally maintain the potential between the control electrode and one principal electrode of said electric discharge device substantially opposite phase to the potential between the principal electrodes of said device thereby to maintain said device in deenergized condition and means for deenergizing said photo-sensitive device to shift the phase of the potential impressed between said control electrode and said principal electrode of said device relative to the potential impressed between said principal electrodes thereby to energize said device.
6. Translating apparatus comprising an electric discharge device including a control electrode and a plurality of principal electrodes immersed in a gaseous medium, means, including a transformer having a secondary equipped with an intermediate tap and a plurality of terminal taps, for applying potentials between the electrodes of said electric discharge device, means for connecting the principal electrodes of said device between a terminal tap and said intermediate tap of said secondary to maintain a predetermined potential between said principal electrodes, an impedance, means for connecting said impedance between said control electrode and the other terminal tap of said secondary, a plurality of additional impedances connected in series with each other, said series connected impedances being of a type such that the individual potentials impressed across them when they are connected in series are in time-quadrature phase relation-
- ship with each other, means for connecting said series connected impedances between the terminal taps of said secondary, a further impedance, means for connecting said further impedance between the control electrode of said device and the junction point of said series connected impedances, said impedances cooperating to normally maintain the potential between the control electrode and one principal electrode of said electric discharge device substantially in opposite phase to the potential between the principal electrodes of said device thereby to maintain said device in deenergized condition, and means for varying the condition of said last-named impedance to shift the phase of the potentials impressed between said control electrode and said principal electrode of said device relative to the potential impressed between said principal electrodes thereby to energize said device.
7. Translating apparatus comprising an electric discharge device including a control electrode and a plurality of principal electrodes immersed in a gaseous medium, means, including a transformer having a secondary equipped with an intermediate tap and a plurality of terminal taps, for applying potentials between the electrodes of said electric discharge device, means for connecting the principal electrodes of said device between a terminal tap and said intermediate tap of said secondary to maintain a predetermined potential between said principal electrodes, an impedance, means for connecting said impedance between said control electrode and the other terminal tap of said secondary, a plurality of additional impedances connected in series, said series-connected impedances being of a type such that the individual potentials impressed across them when they are connected in series are in time-quadrature phase relationship with each other, means for connecting said additional impedances between the terminal taps of said secondary, a photo-sensitive device, said device being normally deenergized, means for connecting said normally deenergized photo-sensitive device between the control electrode of said device and the junction point of said series connected impedances, said photo-sensitive device and said impedances cooperating to normally maintain the potential between the control electrode and one principal electrode of said electric discharge device substantially in opposite phase to the potential between the principal electrodes of said device thereby to maintain said device in deenergized condition, and means for energizing said photo-sensitive device to shift the phase of the potential impressed between said control electrode and said principal electrode of said device relative to the potential impressed between said principal electrodes thereby to energize said device.
8. Translating apparatus comprising an electric discharge device including a control electrode and a plurality of principal electrodes immersed in a gaseous medium, means for supplying potentials between the electrodes of said electric discharge device, said means having an intermediate tap and a plurality of terminal taps, means for connecting the principal electrodes of said device between a terminal tap and said intermediate tap of said potential supply means to maintain a predetermined potential between said principal electrodes, an impedance, means for connecting said impedance between said control electrode and the other terminal tap of said potential supply means, a plurality of additional impedances, means for

- connecting said additional impedances between the terminal taps of said potential supply means, a further impedance, means for connecting said further impedance between the control electrode 5 of said device and the junction point of the impedances that are connected between the terminal taps of said secondary, said impedances cooperating to normally maintain the potential between the control electrode and one principal electrode of said electric discharge device substantially in opposite phase to the potential between the principal electrodes of said device thereby to maintain said device in deenergized condition and means for varying the condition 10 of said last-named impedance to shift the phase of the potential impressed between said control electrode and said principal electrode of said device relative to the potential impressed between said principal electrodes thereby to energize said device.
9. Translating apparatus comprising an electric discharge device including a control electrode and a plurality of principal electrodes immersed in a gaseous medium, means for supplying potentials 15 between the electrodes of said electric discharge device, said means having an intermediate tap and a plurality of terminal taps, means for connecting the principal electrodes of said device between a terminal tap and said intermediate tap of said potential supply means to maintain a predetermined potential between said principal electrodes, an impedance, means for connecting said impedance between said control electrode and the other terminal tap of said potential-supply means, a plurality of additional impedances connected in series with each other, said series connected impedance being of a type such that the individual potentials impressed across them when they are connected in series are in time-quadrature phase- 20 relationship with each other, means for connecting said series connected impedances between the terminal taps of said secondary, a further impedance, means for connecting said further impedance between the control electrode of said device and the junction point of said series connected impedances, said impedances cooperating to normally maintain the potential between the control electrode and one principal electrode of said electric discharge device substantially in opposite phase to the potential between the principal electrodes of said device thereby to maintain said device in deenergized condition, and means for energizing said photo-sensitive device to shift the phase of the potential impressed between said control electrode and said principal electrode of said device relative to the potential impressed between said principal electrodes thereby to energize said device.
10. Translating apparatus comprising an electric discharge device including a control electrode and a plurality of principal electrodes immersed in a gaseous medium, means for supplying potentials between the electrodes of said electric discharge device, and means having an intermediate tap and a plurality of terminal taps, means for connecting the principal electrodes of said device between a terminal tap and said intermediate tap of said potential supply means to maintain a predetermined potential between said principal electrodes, an impedance, means for connecting said impedance between said control electrode and the other terminal tap of said potential-supply means, a plurality of additional impedances connected in series with each other, said series-connected impedances being of a type such that the individual potentials impressed across them when they are connected in series are in time-quadrature phase- 25 relationship with each other, means for connecting said series connected impedances between the terminal taps of said secondary, a further impedance, means for connecting said further impedance between the control electrode of said device and the junction point of said series-connected impedances, and means for varying the condition of one of said impedances, said impedances being so related to each other that when the condition of the last said impedance is varied, the phase of the potential impressed between said control electrode and one of said principal electrodes is shifted between a position in which it is 30 in opposite phase to the potential impressed between said principal electrodes and position in which the potential impressed between said principal electrodes leads the potential impressed between said control electrode and said principal electrode by an angle of substantially less than 180°, whereby said electric discharge device is in deenergized or in energized condition.
